HIS ATTORNEYS.

UNITED STATES PATENT OFFICE.

HERMAN B. WELCH, OF JOPLIN, MISSOURI, ASSIGNOR TO THE MEEKER COMPANY, OF JOPLIN, MISSOURI, A CORPORATION OF MISSOURI.

SKIVING MACHINE.

Application filed August 14, 1925. Serial No. 50,216.

This invention relates to skiving machinery.

An object of the invention is to provide improvements for use in skiving machines whereby strips of leather may be cut to different thicknesses with rounded or beveled edges obtained by cutting the leather from one side of the leather strips, so that the strip produced by operation of the machine has a thick longitudinal central portion and attenuated side edges.

Another object of the invention is to provide adjustable and removable devices for use in connection with existing skiving machines for obtaining the desirable results herein disclosed.

Other objects will appear from the following description, reference being made to the accompanying drawing, in which

Fig. 1 is a cross sectional view of the frame of a skiving machine having the present invention embodied therein.

Fig. 2 is a side elevation with parts shown in section.

Fig. 3 is an enlarged view illustrating important features of the present invention.

Fig. 4 is a cross sectional view showing the shape of a strip of leather obtained by use of this machine.

The machine and the driving mechanism of the machine are of well known commercial type. The frame 1 encloses part of the operating mechanism. A shaft 2 is journaled in the frame and extends toward the front side thereof. A worm gear 3 on the shaft 2 is driven by a worm 4 on a drive shaft 5. An arm 6 supported near the front side of the frame has a rearwardly extended arm 7 on its inner end which maintains alignment with the shaft 2. The shaft 2 cooperates with the extended arm 7 to support the feed roll of the machine the novel structure of which constitutes a part of the present invention.

The machine in which the present invention is embodied also comprises an arm 8 having a depending frame part 9 terminating above the frame 1 and supporting the adjustable presser foot support 10 which is capable of vertical adjustment by an adjusting screw 11 and is held from turning by a structure comprising a flat end portion 12 adjustable in the slots 13 in the lower end of the frame part 9.

The cylindrical knife 14 of the machine is attached to the end of a shaft 15 and is driven by the same driving mechanism from which the feed roll shaft 2 is driven, and in the machine shown the knife 14 turns in a counterclockwise direction (Fig. 1).

The leather strips are fed to the knife 14 and guided in the proper shape for cutting by means of the present invention. The feed roll 16 has one end rotative on the extension 7 and the opposite end clutched to the shaft 2. The feed roll 16 is formed with a circumferential rib or flange 17 having its outer edge rounded and serrated, so that it will feed the strips of leather positively toward the knife 14 which rotates when the feed roll is rotated. The edge of the rib or flange 17 is slightly within the plane of the annular knife 14.

The presser foot 18, the novel structure of which constitutes a part of the present invention, is mounted on a pivot 19 in connection with the lower end of the presser foot support 10. As will be seen by reference to Figs. 1 and 3 the lower edge of the presser foot is concaved upon approximately the same radius of curvature as the radius of curvature of the knife 14 and the feed roll 16.

A spring 20 is attached to the frame part 9 and engages one arm of the presser foot 18 and holds the same against the end of an adjusting screw 21 by adjustment of which the presser foot may be held in any desired relationship to the feed roll and the knife. The lower edge 22 of the presser foot inclines upwardly and laterally and is formed with a recess 23 into which the strip of leather passing through the machine is pressed and given shape by the rib or flange 17. By reference to Fig. 3 it will be seen that the strip of leather 24 by cooperation of the presser foot and the feed roll is fed to the knife 14 in such a way that the knife will bevel both side edges of the strip, producing a strip of the cross sectional shape shown in Fig. 4. This is because the strip of leather passing to the knife is curved transversely on a shorter radius of curvature than the curvature of the knife.

It is apparent that series of feed rolls and presser feet may be provided to skive strips of leather of different widths, thickness and shapes. I contemplate such variation and

such other changes as may be required to adapt the machine for purposes for which it is intended.

I do not restrict myself unessentially, but 5 what I claim and desire to secure by Letters Patent is:—

1. In a skiving machine, the combination 10 with an annular rotary skiving knife, of a feed roll having peripheral longitudinal curvature upon approximately the same radius as the curvature of the knife, a circumferential flange on said roll, and a presser foot having a recess in radial alinement with said flange and cooperating with said 15 feed roll to curve the work transversely upon a shorter radius of curvature than the curvature of the surface of the roll or the curvature of the knife.

2. A skiving machine comprising an an-

nular rotary knife, in combination with a 20 feed roll rotative on an axis at right angles to the axis of the knife, a circumferential flange upon the feed roll extending closer to the edge of the knife than the remainder of the surface of the roll, and a presser foot 25 for pressing the work into contact with the feed roll.

3. A skiving machine comprising an annular rotary knife, in combination with a 30 feed roll rotative on an axis at right angles to the axis of the knife, a circumferential flange upon the feed roll extending closer to the edge of the knife than the remainder of the surface of the roll, and a presser foot 35 for pressing the work into contact with the feed roll, and having a notch in radial alinement with said flange.
